TIE AND METHOD OF MAKING THE SAME

Albert J. Less, Clinton, Iowa, assignor to Joseph
W. Less, Clinton, Iowa

Application July 28, 1933, Serial No. 682,593

9 Claims. (Cl. 2—150)

This invention pertains to scarfs or ties of the "made up" type, and to a mode of constructing the same.

An object lies in providing a structure in a made up tie wherein the body of the same will always properly align itself with the "knot" portion to the end that it will hang in a properly suspended position with respect thereto.

Another object is to provide a "made up" tie wherein the body portion will swing freely from the knot portion and be thus self adjusting and so that it may be readily modeled below said knot portion to suit the designer or wearer.

Further, an object is to so relate the portions of a tie with respect to each other during construction that a minimum of operations only are necessary for the production of the tie and thereby the number of finished ties that can be produced within a given period of time can be increased, thus reducing cost of manufacture.

In order that my invention may be thoroughly understood in all its details I have provided the appended drawing forming part hereof wherein—

Figure 1 shows portions of a tie in perspective assembled according to my method during manufacture.

Figure 2 is a longitudinal section of the same taken on line 2—2 of Figure 1.

Figure 3 is a plan of a stiffening wire and an associated lining entering into the construction of the "knot" of the tie.

Figure 4 is a rear elevation of a tie made according to my invention, the same appearing in perspective.

Figure 5 illustrates in perspective a tubular knot portion shown in dotted lines in Figure 2, and appearing in flat form for sewing, and

Figure 6 is a front elevation of the finished tie.

It may be stated that my tie is of that type illustrated in the pending application of Joseph W. Less, Ser. No. 672,201 filed in the United States Patent Office of the 22nd day of May, 1933 wherein the tie is held in adjusted position at the wearer's collar by a bunching of the collar-encircling band within a tubular knot portion, the present invention being an improvement applicable to that type as well as to ties of other forms such as use an impalement pin for securing the tie in adjustment.

The manner of constructing and finishing the tie herein begins with the assembling of a tie body 1 and the collar encircling band. The said body, or body portion as I shall term it, is usually of a tubular made up form having a narrow neck portion 1' at its upper end. At-

tached to the said neck portion, as part of my invention, is a strip of tape 3 doubled upon itself, its ends being secured as by sewing, for example, either within or outside of said neck portion forming what may be termed a hanger. 60 It may be said, however, that this hanger may be of any other type that will answer the purposes herein to be made known. Upon the back side of the neck portion is now placed one end of a neck-encircling band 2, followed by 65 drawing over the thus related parts a tapering tubular outer knot portion 4 of the tie material of which the body portion 1 is constructed, the small end of the knot portion overlying the previously located end of the band 2. The thus 70 assembled parts are now sewed to each other as at b. While the body portion and the tape 3 are preferably sewn together prior to the acts last described it is clear that, if desired, the two acts may be combined in the one sewing at b. 75

The body portion, band and knot having now been secured relatively, a U-shaped wire 5 is inserted through the loop of the hanger-tape 3, the extremities thereof depending as shown. Next, there is provided an inner knot portion 7 80 preferably of stiff material such as canvas, for example, of substantially the form shown in Figure 1, its ends being lapped upon itself and secured to form pockets 6 into which the extremities of the wire 5 are inserted. 85

The lower free extremity of the outer knot portion 4 is now drawn up around the wire 5 and the inner knot portion 7 as shown in dotted lines in Figure 2 whereupon the open upper end thereof may be machine stitched as at c, Figure 5. The 90 thus stitched end is next folded down upon the rear side of the portion 7 as shown by dotted lines d in said Figure 2.

Thus arranged the tie is now placed in a machine, not shown, and the jaws therefor, not shown, serve by pressure to bend the wire and its canvas covering 7, together with the outer knot portion 4, into tubular form appearing as in Figure 4, the folded end of said outer knot portion lying within the formed tube as d in that figure. 100

The tie is now complete and ready for use, it being observed that in this instance the point at which the band 2 is attached is near the lower portion of the completed knot, this point of attachment being for a tie of the particular type 105 herein and that described in the patent application above referred to.

In a study of Figure 6 it will be seen that the tape 3 hangs from the wire 5 thus suspending the body portion 1 freely from such wire. It is 110

to be noted that since the body portion 1 is suspended freely from the wire 5 by means of the tape 3 it is free to both swing and to shift thereon to thus find a natural pendent position beneath the knot portion even though the covering material of the knot is attached at its lower or small end to such body portion, sufficient freedom being provided by the covering material distant from its place of attachment at *b* to permit such movement, and the tie need never present, therefore, a distorted appearance. Due to the fact that the body portion extends some distance up inside the knot the material thereof where it extends from the knot may be readily modeled to present desired folds, or may be otherwise dressed to suit the fancy. Instead of machine sewing the large end of the covering material 4 at *c* as in Figure 5 the end of such material may be pushed down into the knot as shown in Figure 4 and then sewn by hand at the position *d*.

Due to the manner in which the parts of the tie can be assembled it may be seen that the operations required for sewing are greatly reduced over older methods and therefore the commodity can be produced at low cost.

I claim:

1. In a tie of that type having in its construction a knot portion and a pendent body portion, the combination of a knot portion, a wire secured within the same having a substantially straight portion extending in a transverse direction, a body portion extending at an end thereof into said knot portion including a part extending from the said body portion and engaged about the wire to swing therefrom, said part being relatively narrow as compared with the length of the said straight portion of the wire and free to shift along the same.
2. A tie including a body portion, a neck encircling band attached at one of its ends to one end of said body portion, said band paralleling the longest measurement of the latter, an inner knot portion enclosing the body portion at that end to which the band is attached, and a hanger portion attached to the body portion and to the knot portion freely suspending the former from the latter and arranged to permit those portions to swing one with respect to the other, the place of attachment of the neck encircling band to said body portion being within the knot portion adjacent that end thereof into which the said body portion extends.
3. In a tie, a body portion, a band overlying at one end a part of one end of the said body portion at the back side thereof, an outer knot portion enclosing the thus assembled ends, all of the described parts being secured in connected relation, and an inner knot portion enclosed by the said outer knot portion, said body portion being suspended freely from said inner knot portion and free to move laterally with respect to it.
4. In a tie, a body portion, a band overlying at

one end part of one end of said body portion, an outer knot portion enclosing the thus associated ends of the named parts, all of said parts being secured in connected relation, and an inner knot portion enclosed by said outer knot portion, and means for connecting the inner knot portion and the body portion at a position distant from the place where the band and body portion are secured to each other, the last named portion being free to swing laterally with respect to both knot portions.

5. In a tie, a body portion, a band attached at one end to said body portion near one end thereof at its back side, an outer tubular knot portion enclosing the two and also attached at one end to said body portion at substantially the place of attachment of the said band, an inner knot portion enclosed in the outer knot portion, and means connecting the body portion to the inner knot portion for suspending one from the other.

6. The invention according to claim 5 wherein the point of connection of the band, the outer knot portion, and the body portion lies distant from the free end of said body portion, and distant from the place of connection of the inner knot portion with the main body of the structure.

7. In a method of constructing a tie, the method which includes the steps of placing upon one end of the body portion of a tie one end of the collar encircling band of the tie, placing about the two named parts an outer knot portion, securing together one end of the latter and the said named parts, attaching an inner knot portion to the body portion at a single point, and drawing the outer knot portion over the inner knot portion.

8. In a method of constructing a tie, the method which includes the steps of attaching to one end of the body portion of a tie a suspending portion, placing upon that end of the body portion one end of a collar encircling band, placing about that end of the body portion and the band an outer knot portion, sewing together the body portion and band and one edge of the knot portion, providing a stiffening inner knot portion, attaching the suspending portion to the said inner knot portion remote from the place of sewing, and drawing the said outer knot portion over the said inner knot portion.

9. In a method of constructing a tie, the method which includes the steps of attaching to one end of the body portion of a tie a suspending portion, placing upon that end of the body portion one end of a collar encircling band, placing about that end of the body portion and the band an outer knot portion, sewing together the body portion and band and one edge of the knot portion, providing a substantially flat stiffening inner knot portion, attaching the suspending portion to the inner knot portion remote from the placing of the sewing, drawing over the inner knot portion the said outer knot portion, and bending the knot portions into tubular form.
